UNITED STATES PATENT OFFICE.

ISAAC COATES WILLIAMS, OF PHILADELPHIA, PENNSYLVANIA, ASSIGNOR TO
EMILY WEAVER WILLIAMS, OF SAME PLACE.

WASHSTAND.

SPECIFICATION forming part of Letters Patent No. 613,747, dated November 8, 1898.

Application filed April 20, 1898. Serial No. 678,246. (No model.)

To all whom it may concern:

Be it known that I, ISAAC COATES WILLIAMS, a citizen of the United States, residing at Philadelphia, in the county of Philadelphia and State of Pennsylvania, have invented certain new and useful Improvements in Washstands, of which the following is a full and complete specification, such as will enable those skilled in the art to which it appertains to make and use the same.

This invention relates to washstands; and the object thereof is to provide an improved device of this class with improved means for supplying water thereto and for conveying the waste water therefrom, a further object being to provide a washstand with a sliding tank which is mounted therein and adapted to be drawn out of the front thereof, said tank being adapted to be used as a bath tub or tank and being provided with adjustable water-supply pipes, said tank being also provided with a hinged cover which is adapted to serve as a seat; and with these and other objects in view the invention consists in the construction, combination, and arrangement of parts hereinafter described.

The invention is fully disclosed in the following specification, of which the accompanying drawings form a part, in which—

Figure 1 is a plan view of my improved washstand, showing the bath tub or tank drawn out and the hinged covers thereof open. Fig. 2 is a side view thereof, part of the construction being broken away; Fig. 3, a view similar to Fig. 2, with parts of the apparatus shown in vertical section. Fig. 4 is a central vertical section of my improved washstand, showing the parts folded together; and Fig. 5 is a plan view of the bath tub or tank removed and showing the hinged cover thereof closed, as is also a hinged front and end plate connected therewith, another hinged plate being shown open.

In the drawings forming part of this specification the same parts of my improvement are designated by the same numerals of reference in each of the views, and in the practice of my invention I provide a washstand 6, which may be of the usual or any preferred form and which is provided with a top 7, in which is placed the usual bowl 8,

and the front thereof is provided with a large transverse opening 9, and mounted in the bottom of said stand is a sliding tank 10, which is adapted to be drawn out into the position shown in Figs. 2 and 3 or shoved into the base of said stand, as shown in Fig. 4, and at one or both sides of said tank is a catch 11, which is adapted to operate in connection with a corresponding notch or recess in the side of the stand to prevent the tank from being entirely withdrawn therefrom. My invention, however, is not limited to these means for preventing the entire withdrawal of the tank, and any suitable construction may be provided for this purpose.

Passing vertically up within the stand, adjacent to the back thereof, are two water-supply pipes 12, one of which is shown in full lines in Figs. 3 and 4 and both of which are shown in dotted lines in Fig. 1, and these pipes are each provided at their upper ends with the usual faucets 13, which are controlled by the usual valves 14, and said pipes are designed to supply hot and cold water, which is discharged into the bowl 8 by the faucets 13 in the usual manner.

Connected with the bottom of the bowl 8 is a water-discharge pipe 15, which connects with a waste pipe or conduit 16, which passes backwardly and downwardly through the bottom of the stand, and by means of these pipes the water may be supplied to the bowl 8 and discharged therefrom in the usual manner, and said bowl 8 is provided with an overflow-pipe 17, which communicates therewith near the top thereof at 18, and the lower end of which is also in communication with a pipe 15.

Mounted in one side of the tank 10 are water-pipes 19 and 20, which are shown in Fig. 2 and in dotted lines in Fig. 1, and these pipes connect with a faucet 21, which discharges into the tank 10, and are controlled by valves 22, and the water-pipe 20 is placed in communication with one of the supply-pipes 12 by means of two pipe-sections 23, which are connected at 24 by means of a hinged coupling through which the water is free to pass. One of the sections 23 is connected with the corresponding supply-pipes 12 at 25 by a similar coupling and the other

with the pipe 20 in the side of the tank 10 by a similar coupling 26.

The water-pipe 19 in the side of the tank 10 connects at its inner end with a downwardly-inclined pipe 27, which is shown in full lines in Figs. 2 and 3 and in dotted lines in Fig. 1 and which extends transversely of the back of the tank 10 and which is connected at 26 and on the side of the stand opposite the pipes 19 and 20 with short hinged pipes 23, similar to the pipes 23 on the opposite side, and which are connected at 24 by a hinged coupling and at 25 with one of the supply-pipes 12, this arrangement being clearly shown in dotted lines in Fig. 1 and in full lines in Fig. 3, the construction and arrangement of the hinged pipes 23 and the coupling by which they are connected being the same on each side.

20 The construction of the couplings at 24, 25, and 26 is not shown in section or in detail for the reason that various forms of such couplings are well known and any desired form may be employed.

25 Arranged transversely in the bottom of the stand is a waste-water pipe 28, which is shown in full lines in Figs. 3 and 4 and in dotted lines in Fig. 1, and the rear end of this pipe is in connection with the waste-water pipe 16 at 29, and mounted in the forward open end of said pipe 28 is a telescopic tube 30, which is free to slide in the pipe 28, and the forward end thereof is in communication with the bottom of the tank 10 at 31, and an overflow branch 32 communicates with said tank, near the top thereof, as shown at 33 in Fig. 3. The connection between the pipes 28 and 30 is a water-tight connection, while admitting of the free movement of said pipes one with the other, and when the tank 10 is shoved into the bottom of the stand the pipe 30 is entirely telescopic in the pipe 28, and when said tank is drawn out, as shown in Fig. 3, the pipe 30 is drawn out and the waste water 45 from the tank 10 may be discharged therethrough whenever desired.

The couplings of the pipes 23 are preferably made like ordinary folding gas-pipe couplings and may be tightened by means of 50 nuts or in any desired manner.

The tank 10 is open at the top, as shown at 34 in Fig. 3, and is provided with a cover 35, which is hinged longitudinally thereto, as shown at 36, and adapted to be folded backwardly and supported by a frame 37, which is hinged thereto at 38 and which is adapted to be swung downwardly into the position shown in Fig. 3 when said cover is open and to be folded over the cover when said cover 60 is closed over the tank 10. The front of the stand is provided with a door 39, which is hinged thereto at 40 and which is adapted to be raised in the operation of drawing out the tank or shoving it into the stand, and it will 65 be observed that the cover 35 is hinged to the tank rearwardly of the front of the tank, and when the tank is shoved into the stand and

the door 39 closed the cover 35 and its attachments will be concealed.

The bottom of the cover 35 of the tank 10 is provided with raised seat portions 41, which serve as a seat and by means of which the water in the operation of bathing is free to flow around a person sitting on said cover, as hereinafter described. The cover 35 is also provided at its outer side with a hinged guard-plate 42 and with two hinged end guard-plates 43, and the triangular space between said plates 43 and the plate 42 is filled in with flexible material 44, such as oil-cloth or rubber, and the hinged end plates 43 are provided at their rear sides with supplemental hinged plates 45. These plates are all hinged in such manner that when folded outwardly, as shown in Figs. 1 and 3, they occupy a downwardly-inclined position, and in practice a spray-nozzle, if desired, may be connected with the faucet 21, and a party when washing or bathing sits on the seats 41 on the hinged cover 35 with his feet in the tank 10, and the water may be sprayed over his or her person, as will be readily understood, and the guard-plates 42, 43, and 45 and the flexible connections 44 between the plates 42 and 43 are intended to prevent the water from falling on the floor or carpet, and the water as it flows from the body of the bather is collected by said plates and the seat 35 and flows back into the tank 10, as will be readily understood.

100 My improved combination washstand and bath-tank are simple in construction and operation, and it will be apparent that changes in and modifications of the construction herein described may be made without departing from the spirit of my invention or sacrificing its advantages.

105 In Fig. 5 I have shown the method of folding the guard-plates 42, 43, and 45 over the seat 35, and in this operation the guard-plate 42 is first folded over said seat. The supplemental plates 45 are then folded over the end plates 43, and said end plates are then folded over the plate 42, and the seat 35 is then folded over the tank, and the frame 37 rests 115 thereon.

Having fully described my invention, I claim as new and desire to secure by Letters Patent—

110 1. A combination washstand and bath-tank, said stand being provided in the top thereof with the usual bowl, and in the front with an opening above which is a hinged door, a tank mounted in the bottom of said stand and adapted to slide out and in through said 115 opening, water-supply pipes which pass upwardly through said stand and are provided with faucets for said bowl, water-escape pipes connected with the bottom of said bowl, water-pipes mounted in the side of said tank 120 and provided with a faucet, said last-named pipes being in communication with hinged section-pipes arranged in said stand and in communication with said supply-pipes, and 125 130

a water-escape pipe consisting of telescopic sections arranged in the bottom of said stand, one of said sections being in communication with said tank, substantially as described.

- 5 2. A combination washstand and bath-tank, said stand being provided in the top thereof with the usual bowl, and in the front with an opening above which is a hinged door, a tank mounted in the bottom of said stand and adapted to slide out and in through said opening, water-supply pipes which pass upwardly through said stand and are provided with faucets for said bowl, water-escape pipes connected with the bottom of said bowl, water-pipes mounted in the side of said tank and provided with a faucet, said last-named pipes being in communication with hinged section-pipes arranged in said stand and in communication with said supply-pipes, and a water-escape pipe consisting of telescopic sections arranged in the bottom of said stand, one of said sections being in communication with said tank, said tank being also provided with a hinged cover which is adapted to open outwardly and serve as a seat, and said cover with guard-plates hinged to the front side and the ends thereof, substantially as described.

- 30 3. A combination washstand and bath-tank, said stand being provided in the top thereof with the usual bowl, and in the front with an opening above which is a hinged door, a tank mounted in the bottom of said stand and adapted to slide out and in through said opening, water-supply pipes which pass upwardly through said stand and are provided with faucets for said bowl, water-pipes connected with the side of said tank and provided with a faucet, said last-named pipes being in communication with hinged section-pipes arranged in said stand and in communication with said supply-pipes, and a water-escape pipe consisting of telescopic sections arranged in the bottom of said stand, one of said sections being in communication with said tank, said tank being also provided with a hinged cover which is adapted to open outwardly and serve as a seat, and said cover with guard-plates hinged to the front side and the ends thereof, the side guard-plates and end guard-plates being provided with flexible connections, substantially as described.

- 45 4. A combination washstand and bath-tank, said stand being provided in the bottom of the front thereof with an opening above which is a hinged door, and in the top thereof with the usual bowl, water-supply pipes for said bowl, and a water-escape pipe connected with the bottom of said bowl, a tank mounted in said stand adapted to slide out and in through said opening, water-pipes mounted in one side thereof and in communication with said water-supply pipes by means of short hinged

55 pipes, a telescopic water-escape pipe in the bottom of said stand, one section of which is in communication with said tank, and said tank being also provided with a hinged cover, which is adapted to serve as a seat, substantially as described.

60 5. A combination washstand and bath-tank, comprising a stand provided with a bowl, water-supply pipes which communicate therewith, and water-escape pipes leading therefrom, a sliding tank mounted in said stand and adapted to move through an opening in the front thereof, said stand being also provided with a hinged door above said tank and said tank with water-pipes in the side thereof, in connection with said water-supply pipes by means of short hinged pipes for supplying water to said tank, and a telescopic water-escape pipe mounted in the bottom of said stand, one section of which is in communication with said tank, substantially as described.

65 6. A combination washstand and bath-tank, comprising a stand provided with a bowl, water-supply pipes which communicate therewith, and water-escape pipes leading therefrom, a sliding tank mounted in said stand and adapted to move through an opening in the front thereof, said stand being also provided with a hinged door above said tank and hinged water-pipes in connection with said water-supply pipes for supplying water to said tank, and a telescopic water-escape pipe mounted in the bottom of said stand, one section of which is in communication with said tank, said tank being also provided with a hinged cover which is adapted to serve as a seat, substantially as described.

70 7. The combination with a washstand, of a sliding tank mounted in the bottom thereof and adapted to move out and in through an opening formed in the front thereof, said stand being also provided with a bowl in the top thereof, pipes for supplying water to said bowl, and water-escape pipes connected with the bottom thereof, water-pipes in the side of said tank for supplying water thereto, said pipes being in communication with said water-supply pipes, by means of folding couplings, and a water-escape pipe mounted in the bottom of said stand, and consisting of telescopic sections, one section of which is in communication with the bottom of said tank, substantially as described.

75 In testimony that I claim the foregoing as my invention I have signed my name, in presence of the subscribing witnesses, this 15th day of April, 1898.

ISAAC COATES WILLIAMS.
